ASSEMBLY FIXTURE

Alexander H. Lewis, Springfield, Mass.

Application November 16, 1945, Serial No. 629,206

4 Claims. (Cl. 29—208)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates in general to a device for making press-fit assemblies.

A particular object of the invention is to provide a device for assembling a plunger in one end of a helical spring, the plunger being provided with a mating portion that requires a press-fit assembly.

In this particular application, assembly has heretofore been accomplished manually, the operation being slow and the results sometimes variable. By providing mechanical means in accordance with this invention for accomplishing this assembly, the production rate has been greatly increased and uniformity of assembly has been realized.

While this invention covers a device for assembling a plunger or pin in one end of a helical spring, it is to be distinctly understood that many other applications of the principle herein exemplified will occur to those skilled in the art and that the application of the invention is not limited to this specific purpose.

The specific nature of the invention as well as other objects and advantages thereof will clearly appear from a description of a preferred embodiment as shown in the accompanying drawings in which:

Fig. 1 is a transverse elevation of the assembled machine.

Fig. 2 is a longitudinal elevation of same.

Fig. 3 is a transverse elevation, partly cut away, of a modified structure.

Fig. 4 is a longitudinal elevation of the modified structure.

As shown in Fig. 1, the invention comprises a base 5, a disk-like cylinder 10 rotatably mounted on the base and having a series of circumferentially spaced assembly holes 11. The axes of holes 11 lie in a plane perpendicular to the axis of the cylinder and a cam-arm 15 is pivotally and resiliently mounted in tangential relation to the cylinder, embracing the plane of the axes of holes 11.

The cylinder 10 is arranged to be rotated about a horizontal axis by any suitable source of motive power (not shown). In this particular application, the cylinder is rotated counterclockwise as shown in Fig. 1.

Holes 11 are arranged with their axes tipping forwardly with respect to the direction of rotation of the cylinder for a purpose to be shown later. This forward pitch of assembly holes 11 is shown in the preferred application as about twenty degrees but will vary with the application.

The cam-arm 15, having the general form of a

circular arc, is pivotally secured at its lower end to base 5 by means of a stud 20 with the concave camming face 17 adjacent the downwardly moving side of cylinder 10. The concave face 17 has a radius of curvature somewhat greater than the radius of cylinder 10 and is arranged with the mid-section of the concave face 17 resiliently maintained tangent to the periphery of the cylinder, the ends of the camming face 17 therefore being at some distance from the cylinder. Progressively decreasing clearance is thus provided between camming surface 17 and cylinder 10 from the upper end 19 of camming surface 17 down to the point of tangency 18 and progressively increasing clearance from point 18 down to the lower end 21 of camming surface 17.

A flat spring 61 is provided for resiliently maintaining cam-arm 15 in tangential relation with cylinder 10 for a reason to appear later. A pair of spaced arms 60 is secured to the free end of cam-arm 15 in projecting relation and functions as a guide for such cam member.

A chute 25 is provided for catching and guiding assembled units to any convenient receptacle (not shown) after discharge from the bottom of cylinder 10.

In operation, cylinder 10 is rotated (counterclockwise as shown in Fig. 1) at about 3 R. P. M. The operator manually places a helical spring 30 endwise in each hole as it comes up. A plunger 31 with a cylindrical shank 32 arranged for assembly in spring 30 is then manually inserted loosely in the upper end of each spring. As the cylinder rotates, the spring 30 and plunger 31 are carried under the cam-arm 15, the plunger 31 being engaged thereby and, because of the progressively decreasing clearance between cylinder 10 and cam-arm 15, the plunger 31 is cammed inwardly and shank 32 is forced into assembly in spring 30.

In order to prevent plunger 31 from tipping out of alignment with the axis of spring 30 when engaged by cam-arm 15, assembly holes 11 are arranged with a forward pitch of about twenty degrees, it having been found in this application that at this angle the tendency to tip is reduced to minimum and the plungers are maintained in axial alignment with the springs while being pressed into assembly. Holes 11 are of such depth that at the point of tangency 18, plunger 31 is seated properly in spring 30. In this application, the spring 30 is set solid at this point, it being necessary because of the tight fit between spring 30 and plunger shank 32.

The pivotal mounting and resilient support for cam-arm 15 has been provided so that if for any reason, such, for example, as an overlength spring 30 or oversize plunger 31, the plunger cannot be moved inward to the usual assembly position, cam-arm 15 can spring outward and al-

low the defective assembly to pass without damage to either the assembly or the machine.

As the cylinder 10 rotates and assembly holes 11 move toward the underside of the cylinder, assemblies drop out into chute 25. However, in some applications, particularly when the springs are of excessive length, there is a tendency for the assemblies to stick in the assembly holes 11. In such cases it has been found that by terminating the camming surface 17 by means of the sharp shoulder 22, while the spring is still under some compression, the assemblies tend to pop out of the assembly holes 11 as a result of the sudden release from compression and thereby overcome the tendency to stick. It should be noted that arms 60 function also as a safety device to prevent the operator's fingers from being carried under the cam-arm 15.

In case plunger 31 is of such length that it would project unduly from assembly hole 11, a modification as shown in Fig. 3 meets the requirements of the situation.

In this modification, a cylinder 42 is rotatably mounted on a base 41, the cylinder being provided with assembly holes 44 of a depth sufficient to hold an unassembled spring and plunger, the assembly holes being arranged in a manner similar to the original design. A circumferential slot 46 is provided in cylinder 42, the width of this slot being less than the diameter of assembly holes 44, the slot being disposed so as to embrace their axes and extend inwardly somewhat beyond the point at which the spring and plunger to be assembled will be properly engaged.

In this case, a cam-arm 50, similar to cam-arm 15 except that it is thin enough to slide freely in circumferential slot 46, is pivotally and resiliently mounted on base 41 with the concave camming edge 51 engaged in slot 46. Camming edge 51 is arranged so that the upper end 52 is outside of the curved surface of cylinder 42 thereby providing clearance for the unassembled springs and plungers being carried thereunder. A series of longitudinal slots 54 is provided in the cylinder 42, each assembly hole 44 being longitudinally intersected by one of the slots 54 so that the operator will be able to push out any assembly that may become jammed in an assembly hole 44.

While in the modifications described the cylinder has been shown as rotating and the cam member as fixed, it should be understood that this is merely a preferred arrangement and the device would function equally well if the cam member rotated. In other words only relative movement between the cylinder and cam member is required.

It is therefore apparent that the above described invention provides a simple apparatus capable of automatically effecting press-fit assemblies, such as a plunger and spring assembly, with speed and economy.

I claim:

1. An apparatus for making press-fit assemblies comprising, a base, a cylinder rotatably mounted on said base, said cylinder having a plurality of angularly spaced holes therein, said holes being arranged with their axes in a plane perpendicular to the axis of the cylinder, each of said holes being adapted to receive a set of parts to be press-assembled so that before assembly the outer part projects out of the hole, a cam member pivotally mounted on the base and arranged so that during rotation of the cylinder the holes pass adjacent the cam member, and a

spring mounted on the base and engaging the cam member, whereby said cam member is resiliently maintained adjacent the cylinder.

2. An apparatus for making press-fit assemblies comprising, a base, a cylinder rotatably mounted on said base, said cylinder having a plurality of angularly spaced holes therein, said holes being arranged with their axes in a plane perpendicular to the axis of the cylinder, each of said holes being adapted to receive a set of parts to be press-assembled so that before assembly the outer part lies wholly within the hole, the cylinder being provided with a circumferential groove embracing the axes of said spaced holes, and a cam member mounted on the base and engaged in said circumferential groove.

3. An apparatus for making press-fit assemblies comprising, a base, a cylinder rotatably mounted on said base, said cylinder having a plurality of angularly spaced holes, said holes being arranged with their axes in a plane perpendicular to the axis of the cylinder, each of said holes being adapted to receive a set of parts to be press-assembled, and a spring biased cam member pivotally mounted on the base and disposed so that as the cylinder is rotated the axes of the holes lie in a plane embraced by the cam member, said cam member having a concave profile with a radius somewhat greater than said cylinder with the mid-section thereof being tangent to and facing the cylinder, said profile being arranged so that as the cylinder is rotated the clearance between the cylinder and the cam member in the plane of the axes of the holes first decreases through the assembly range and then increases to disengage the cam member from the assembly.

4. An apparatus for making press-fit assemblies comprising, a base, a cylinder rotatably mounted on said base, said cylinder having a plurality of angularly spaced holes therein, said holes being arranged with their axes in a plane perpendicular to the axis of the cylinder, each of said holes being adapted to receive a set of parts to be press-assembled, and a spring biased cam member pivotally mounted on the base and arranged so that as the cylinder is rotated the axes of the holes lie in a plane embraced by the cam member, said cam member having a concave profile with a radius somewhat greater than said cylinder with the mid-section thereof being tangent to and facing the cylinder, said profile being disposed so that as the cylinder is rotated the clearance between the cylinder and the cam member in the plane of the axes of the holes decreases through the assembly range and then terminates abruptly in a shoulder thereby suddenly releasing the assembly from compression as the cylinder is rotated.
